INVENTOR:

Ernest Hunold

by Chas. H. Luther

ATTORNEY:

UNITED STATES PATENT OFFICE.

ERNEST HUNOLD, OF PROVIDENCE, RHODE ISLAND.

CONVERTIBLE SOAP-HOLDER.

1,275,433.

Specification of Letters Patent. Patented Aug. 13, 1918.

Application filed May 8, 1918. Serial No. 233,213.

To all whom it may concern:

Be it known that I, ERNEST HUNOLD, a citizen of the United States, residing at Providence, in the county of Providence and 5 State of Rhode Island, have invented a new and useful Improvement in Convertible Soap-Holders, of which the following is a specification.

My invention has reference to an improvement 10 in shaving utensils and more particularly to an improvement in a convertible soap holder, whereby a coffee-mug, drinking glass, cup or similar article may be converted into a shaving-mug and a more sanitary 15 shaving-mug produced than has heretofore been done.

Shaving-mugs having the soap holder or dish formed integral with the mug are unsanitary, as it is extremely difficult to cleanse 20 the inside of the mug under the soap holding portion of the mug.

The object of my invention is to produce a separable, adjustable and sanitary soap holder that may be applied to a coffee-mug, 25 drinking-glass or the like and thereby convert either of them into a sanitary shaving-mug which may be easily and quickly cleansed by removing the soap holder.

My invention consists in the peculiar and 30 novel construction of a convertible soap holder adapted to convert a water-glass, coffee-mug, cup or the like into a shaving-mug, said convertible soap holder having details of construction, as will be more fully 35 set forth hereinafter and claimed.

Figure 1 is a top view of a coffee-mug provided with my improved convertible soap holder, thereby converting the coffee-mug into a sanitary shaving-mug.

Fig. 2 is a vertical sectional view through 40 the mug showing the convertible soap holder in position in open top of the mug.

Fig. 3 is a top view of the convertible soap holder.

Fig. 4 is a front view of the convertible soap holder.

Fig. 5 is a side view of the convertible soap holder.

Fig. 6 is an enlarged detail sectional view 50 taken on line 6. 6 of Fig. 4, through the locking bolt, and

Fig. 7 is an enlarged detail sectional view taken on line 7. 7 of Fig. 6, through a guide-way.

55 In the drawing, 8 indicates a coffee-mug and 9 my convertible soap holder. The

coffee-mug 8 has the usual handle 10 and inner walls 11 and bottom 12.

My improved convertible soap holder 9 is formed of sheet metal and consists of a semi-circular flat base plate 13, having a central spring clip 14 which extends up from the rounded edge of the base plate 13, over the edge or lip of the mug and down on the outside of the mug, where it terminates in an outwardly bent end 15. A front plate 16 is bent up from and at right angles to the base plate and has a concaved upper edge 17, a concaved portion 18 at each end, a central bolt hole 19 and a T shape guide 20 adjacent each end of the front plate and bent at right angles from the front plate. Two flat adjustable supporting arms 21, 21 are adjustably secured to the front plate 16 by a bolt 22 and knurled nut 23, the bolt 22 extending through the bolt hole 19 in the front plate 16 and through a slot 24 in the inner end of each supporting arm 21 and they are further secured by the T shaped guides 20, 20 each of which extend through a slot forming 75 a guide-way 25 in each of the supporting arms 21, 21. The supporting arms 21, 21 overlap each other at their inner ends and each has a hook shaped outer end 26 which goes over the edge or lip of the mug and with 80 the spring clip 14 holds the soap holder in place in the mug.

By loosening the nut 23 and placing the soap holder over a coffee-mug or drinking glass the soap holder is practically self adjusting, as it is only necessary to push the supporting arms 21, 21 toward each other until the ends 26, 26 fit the mug or glass and then tighten the nut 23 to convert the mug or glass into a shaving-mug. After 90 use the convertible soap holder is removed from the mug or glass when the entire side walls 11 and the entire bottom 12 of the mug or glass may be easily, quickly and thoroughly cleansed. The convertible soap 95 holder being of sheet metal, may then be sterilized by dropping the same into hot water.

It is evident that the construction of my improved convertible soap holder could be 105 changed or modified within the scope of the appended claims.

Having thus described my invention I claim as new:

1. A convertible soap holder having a 110 semi-circular base plate, supporting means on the semi-circular part of the base plate,

a front plate on the base plate and supporting means at each end of the front plate, said supporting means being adapted to go over the edge of a mug or the like, for the 5 purpose as described.

2. A convertible soap holder having a semi-circular base plate, a spring clip on the base plate, a front plate, arms on the front plate adapted to go over the edge of a mug 10 or the like and means for adjustably securing the arms to the front plate, for the purpose as described.

3. A convertible soap holder having a semi-circular base plate, a spring clip on the 15 base plate adapted to go over the edge of a

mug or the like, a front plate bent up from the base plate, two sidewise extending arms on the front plate, each arm having a slot adjacent its inner end, a hook-shaped outer end and a slotted guide-way adjacent the 20 hook-shaped ends, a bolt extending through a hole in the front plate and through the slots in the arms, a knurled nut on the bolt and T shaped guides on the front plate extending through the slotted guide-ways in 25 the arms, for the purpose, as described.

In testimony whereof, I have signed my name to this specification.

ERNEST HUNOLD.
